(57) CLAIM

The ornamental design for a combination stove and counter top, as shown and described.

DESCRIPTION

FIG. 1 is a front perspective view of a combination stove and counter top;

FIG. 2 is a front elevation view of FIG. 1;

FIG. 3 is a rear elevation view of FIG. 1;

FIG. 4 is a left side elevation view of FIG. 1, the right side elevation view being a mirror image thereof;

FIG. 5 is a top plan view of FIG. 1; and,

FIG. 6 is a bottom plan view of FIG. 1.

The broken lines shown in the drawings depict portions of the combination stove and counter top that form no part of the claimed design.
